UNITED STATES PATENT OFFICE

MOREHEAD PATTERSON, OF NEW YORK, N. Y., ASSIGNOR TO AMERICAN MACHINE & FOUNDRY COMPANY, A CORPORATION OF NEW JERSEY

CIGARETTE PACKAGE

Application filed May 29, 1929. Serial No. 366,806.

This invention relates to boxes for cigarettes, cigars, or the like, made of stiff paper or cardboard and designed to protect the cigarettes against being crushed or injured prior to use. This type of package is often troublesome to open, and to remove cigarettes or the like one by one as used, and to close after such removal.

It is one of the principal objects of the present invention to provide a package of this type which may be readily opened and the cigarettes removed one by one, the package being easy to close after a cigarette has been removed. To this end, it is an object of the invention to so construct the package that the package may be closed and opened and a single cigarette removed therefrom by the thumb of the same hand which grips the package, so that the other hand may be left free. In pursuance of this object, a thumb slot near one side of the front of the package is provided so that cigarettes arranged transversely thereof may be conveniently rolled by the thumb out of the package, without the awkwardness attendant on cramping the thumb to a position at the center of the package. Still another object is to provide a package which will give greater protection to its contents than the usual soft paper package, yet which will be simple and inexpensive to make.

With these and other objects in view, the invention consists in certain constructions and combinations which will be hereinafter more fully described and then more particularly pointed out in the appended claims.

In the accompanying drawings which form a part of this specification and in which like characters of reference indicate the same or like parts:

Fig. 1 is a plan view of the blank of a box made in accordance with the invention;

Fig. 2 is a front view of the folded and closed box, resulting from the blank shown in Fig. 1;

Fig. 3 is a cross section on the line 3—3 of Fig. 2; and

Fig. 4 is a cross section on the line 4—4 of Fig. 2.

In carrying the invention into effect, there

is provided a box for cigarettes or the like having a vertical slot in its front side located eccentrically in order to render it convenient to the thumb for rolling cigarettes out of the package when the package is gripped by its front and back, which package has a top opening into which said slot opens, and a movable flap for closing the box. In the best constructions, said movable flap includes top and front portions for closing the top opening and the slot. Preferably, finger operable means are provided for holding the flap closed, which means comprises in the best constructions a diagonal slit at one corner of the front adapted to receive a tongue of the flap, formed by notching the lower edge of the flap.

The above parts may be widely varied in construction within the scope of the claims for the particular structure selected to illustrate the invention is but one of many possible concrete embodiments of the same. The invention, therefore, is not to be restricted to the precise details of the structure shown and described.

Referring to the drawings, as shown in Fig. 1, the blank which is of stiff paper or light cardboard, comprises a back portion 5 having lateral side forming flaps 6 and 7 folded along the lines 8 and 9. Connected to the bottom edge of the back portion is a bottom forming extension 10, provided with laterally extending pairs of ears 11 and 12. The front of the package 13 is connected to the bottom along the fold line 14 and is provided with side forming flaps 15 and 16 which are folded along the lines 8 and 9, and pasted to the side flaps 6 and 7 to form the sides of the package. The flaps 7 and 16 are left unpasted for perhaps three-quarters of an inch at their upper ends for a purpose which will presently appear.

The front portion of the box, 13, is provided with a broad slot 17 which is eccentrically located so as to be convenient to the thumb when the package is held between the thumb on the front side of the package and the fingers on the back side of the package. This slot 17 opens onto the upper edge of the front side of the box and onto the top

opening of the box. This slot is broadened near the aforesaid upper edge at 18, for added convenience in thumbing cigarettes one by one out of the package. The lower left hand corner of the front portion 13 is provided with a diagonal slit 19 for a purpose to be presently described.

For the purpose of closing the top opening of the package and for covering the front 10 side of said package and the slot 17 therein, a flap 20 is provided with a top closing portion 21 joined to the top of the back portion of the box 5 on the fold line 22. This flap is centrally notched at its free edge by a 15 broad notch 23 designed to provide a convenient thumb hold for opening the package when held as above described. This notch also forms a tongue 24 near the lower left hand corner of the flap located in proper 20 position to enter the slit 19 and thereby maintain the flap in closed position. A cutout 26 at this corner of the flap 20 is preferably made in order to make a conveniently narrow tongue.

25 At the right hand lower corner of the flap 20 a laterally extending tongue 25, which is bent at right angles to the plane of the flap, is provided for further securing the flap in closed position, this tongue entering between 30 the side flaps 7 and 16 in a pocket formed by the unpasted portions thereof above referred to.

This tongue 25 serves to securely close the package prior to sale and use thereof, particularly since it is contemplated that the revenue stamp will be pasted over this tongue.

It will be seen from an examination of Figs. 2 and 4, that once the package is unsealed by breaking the revenue stamp and 40 pulling out the tongue 25, the cigarettes, which are arranged transversely with respect to the vertical slot 17, that is with their lengths parallel to the top and bottom of the package, may be conveniently removed 45 therefrom one by one as used, by one hand alone. In so doing, the package will be gripped between the thumb on the front side of the package and the fingers on the back side of the package. The ball of the thumb, 50 or perhaps the nail will be inserted in the notch 23 and pushed away from the slit 19, thus pulling out the tongue 25, whereupon the flap 20 will be opened and the cigarettes may be pushed out of the top opening onto 55 the portion 21 of the flap by the thumb engaging the cigarettes through the slot 17. After a cigarette has been removed, the user, still holding the package, can by raising his thumb and pressing the tongue 24 into and 60 down in slot 19, close the package, thereby protecting the cigarettes and keeping tobacco crumbs out of his pocket until ready for another cigarette, etc. The package is made more convenient for this purpose by reason 65 of the ears 11 which lift one row of cigarettes,

as shown in Fig. 3, into staggered relation with respect to the cigarettes in the other row, whereby one cigarette is always on top. This also has the advantage that it makes possible a thinner package and makes the cigarettes less subject to being crushed. It will be noted that the ears 12 are folded out of the way, flat against the bottom 10 of the package.

What is claimed is:

1. A box for cigarettes or the like having an acentrically located, vertical slot in its front convenient to the thumb when the box is gripped by its front and back, a top opening into which said slot opens, and a movable flap for closing said box, said flap including top and front portions for closing top opening and said slot, and finger operable means for holding the flap closed, said means including a tongue extending longitudinally of said flap, and a tongue extending transversely from said flap, the box being provided with a slit adapted to receive said longitudinally extending tongue and a pocket adapted to receive said laterally extending tongue when it is bent out of the plane of said flap.

2. A box for cigarettes or the like having an acentrically located vertical slot in its front convenient to the thumb when the box is gripped by its front and back, a top opening into which said slot opens, and a movable flap for closing said box, said box having a depth from front to back approximately equal to the width of two cigarettes whereby the cigarettes are arranged in two adjacent rows therein, and means for staggering the cigarettes in one row with respect to those in the other said means comprising integral ears offset from the material forming the bottom of the box.

3. A box for cigarettes or the like having an acentrically located vertical slot in its front convenient to the thumb when the box is gripped by its front and back, a top opening into which said slot opens, and a movable flap for closing said box, said flap having a laterally extending tongue at its lower end on one corner thereof, one side of said box being provided with a pocket adapted to receive said tongue.

4. A box for cigarettes or the like having a top opening and a movable flap for closing said opening and covering the front of said box, said front and flap having means cooperating to hold the flap closed, and a tongue at one corner of said flap, one side of said box being provided with a pocket to receive said tongue when it is bent out of the plane of said flap.

5. A box for cigarettes or the like having a depth from front to back approximately equal to the width of the cigarettes whereby cigarettes will be transversely arranged in two rows therein, and means for staggering the cigarettes in one row with respect to

those in the other, said means comprising integral ears offset from the material forming the bottom of the box adjacent the sides of the box.

5 6. A box for cigarettes or the like having a depth from front to back approximately equal to the width of the cigarettes whereby cigarettes may be transversely arranged in two rows therein, and means for staggering the cigarettes in one row with respect to those in the other, said means comprising a pair of integral ears offset from the material forming the bottom of the box.

10 7. A folding box blank comprising a back portion provided with lateral side forming flaps, a bottom and front forming extension on said back portion, and a top and front covering flap extending from said back portion, said flap being provided with a laterally extending tongue on one corner thereof, and said extension being provided with lateral side forming flaps which are adapted to be secured to the flaps on said back portion to form the sides of the box and a pocket adapted to receive said tongue.

15 8. A folding box blank comprising a back portion provided with lateral side forming flaps, a bottom and front forming extension on said back portion, and a top and front covering flap extending from said back portion, said extension being provided with a plurality of adjacent ears adapted to be offset with respect to each other to support articles in the completed box in different relative positions.

20 35 In testimony whereof, I have signed my name to this specification.

MOREHEAD PATTERSON.
